UNITED STATES PATENT OFFICE.

JAMES W. SMALLMAN, OF BLACKDOWN, NEAR LEAMINGTON, ENGLAND.

SINGLE-TRIGGER MECHANISM FOR DOUBLE-BARREL GUNS.

1,160,333.

Specification of Letters Patent. Patented Nov. 16, 1915.

Application filed September 25, 1909. Serial No. 519,643.

To all whom it may concern:

Be it known that I, JAMES WILLIAM SMALLMAN, a subject of the King of Great Britain and Ireland, of Blackdown, near 5 Leamington, in the county of Warwick, England, have invented a Single-Trigger Mechanism for Double-Barrel Guns, of which the following is a specification.

Figure 1 is a view partly in side elevation and partly in section of an action-body with the trigger-plate attached, and the single-trigger mechanism ready for firing the right barrel first. Fig. 2 is a side elevation of the trigger-plate and single-trigger mechanism just after the first pull on the trigger has released the right lock; the sear-tails and the safety-bolt being included in their proper relative positions. Fig. 3 is a view, similar to Fig. 2, showing the parts directly 20 after the involuntary release; the trigger having been forced to return about half-way to its normal position while the rocker reaches its intermediate position. Fig. 4 is an end elevation of the trigger. Fig. 5 is a 25 side elevation of the catch. Fig. 6 is a plan corresponding with Fig. 5. Fig. 7 represents the selective side. Fig. 8 is a plan corresponding with Fig. 7. Fig. 9 is a side elevation of the bar that affords communication between the fastening bolt and the plunger. Fig. 10 is a plan corresponding with Fig. 9. Fig. 11 is a view, partly in side elevation and partly in section, showing a special trigger and a catch without 30 steps. Fig. 12 is a plan (drawn to a larger scale) illustrating a modification of the selective slide. Figs. 13 and 14 are similar views with the modified slide in different 35 positions.

Many systems of mechanism have been tried for overcoming the difficulties due to the involuntary pull which occurs after the firing of the first barrel. Timed mechanisms may prove too fast, in which case the second 40 barrel is prematurely discharged; or too slow, balking the shooter when he attempts to fire the second barrel. Premature discharges of the second barrel and balking also happen with the ordinary "three-pull" 45 mechanisms.

The object of the present invention is to produce simple and compact mechanism that will permit both barrels to be fired in quick succession without allowing the second barrel to be unintentionally discharged.

The principal features of novelty are a spring-impelled rocker with dependent arm, a catch that engages first by one bent and then by another bent for retaining the said rocker in its normal and intermediate positions, and a trigger nicked to bed against the arm. 60

The extremely short release of the trigger after the nose of the catch has been lifted by the involuntary pull above the second 65 bent is a most important characteristic of this construction.

The trigger A has two walls α and α' ; and a catch B, placed between these, works on the trigger-pin α'' . The walls α and α' have 70 stops i and i' . The catch has a nose b . A slide C capable of occupying two positions is supported in grooves d and d' above the catch B. A V-shaped spring E carried by the catch B presses against the slide C. 75 There are two steps R and L' on the slide C; and two steps R'' and L on the catch B. The steps R and L serve for "right-left"; and the steps L' and R'' for "left-right." A rocker F is mounted in the trigger-plate 80 H on a horizontal pivot h ; an arm f on the rocker F projecting downward behind the trigger A. A plunger J actuated by a strong spiral spring K enters a hole in an abutment h' on the trigger-plate H; the 85 head j of the plunger, upon which two bents M and M' are cut, being hinged by the pin j' to the top of the rocker F. The trigger A, opposite the arm f, has two nicks N and N'. A bar P fitting in a channel h'' on the 90 box H' affords communication between the fastening bolt Q and the plunger J. A lug p extends from the bar P over the slot s . A lever T with a protruding foot t is jointed in the trigger A on the pin t'' . The 95 slide C has a notch c for the head t' of the lever T. A spur V on the slide C goes under the leg w of the safety-bolt W. A prolongation S on the front of the trigger A underlies the trigger-plate H. X is the 100 right and X' the left sear-tail; α being the right and α' the left safety sear-tail.

While the nose b of the catch B rests in the bent M, thereby retaining the plunger J and the rocker F in their normal positions, the spring E pressing against the slide C holds the step R in contact with the sear-tails X and α ; a space existing between the step L' and the sear-tails X' and α' . When the trigger A is first pulled the stops i and 110

i', bearing against the steps *R''* and *L*, lift the catch *B*, the nose *b* leaves the bent *M* and the step *R* raises the sear-tails *X* and *x* sufficiently to free the tumbler of the right lock. The sear-tails *X* and *x* (Fig. 2) are fully raised by the action of the right tumbler in falling. The nick *N* hits against the arm *f*, which keeps the step *L* out of contact with the sear-tails *X'* and *x'*. The pressure of the finger on the trigger *A* being now relieved by the recoil of the gun, the rocker *F* turns until, its arm *f* leaving the nick *N*, the bent *M'* comes against the nose *b*. After the first pull, the nick *N* lies in the path of the arm *f* (Fig. 2). Consequently, the arm *f*, in leaving that nick, causes the trigger *A* (through the agency of the slide *C* and the elastic medium of the spring *E*) to lower the nose *b* of the catch *B* into the path of the bent *M'*. The head *j* (Fig. 3) of the plunger *J* advancing beneath the stops *i* and *i'* limits the onward movement of the trigger *A*. The involuntary pull, easily overcoming the resistance due to the engagement of the nose *b* with the bent *M'* drives the trigger *A* back until the nick *N'* arrives against the arm *f*. The nose *b* of the catch *B* is thus brought above the bent *M'*. The rocker *F* then goes into the extreme position; the arm *f* escaping from the nick *N'*. A very short release of the trigger *A* is sufficient to permit the arm *f* to escape. The step *L* is thereupon (held by the spring *E* against the stop *i'*) in contact with the sear-tails *X'* and *x'*; the head *j* of the plunger *J* having run under the nose *b* of the catch *B*. The spring *E* permits the arm *f* (in escaping from the nick *N'*) to pull the stop *i'* slightly away from the step *L*; but immediately afterward takes up the play ready for the firing of the left barrel. The sear-tails *X* and *x*, having been fully raised (Fig. 2), are out of reach when the left barrel is fired. The thumb-lever *Y*, on being turned, forces back the fastening bolt *Q* and the bar *P*; the plunger *J* and the rocker *F* going into their normal positions. The automatic action of the safety-bolt *W* is not interfered with, because the leg *w* moves the trigger *A* downward under the pressure of the spring *E* by the leg *w* while the nose *b* of the catch *B* is rising out of the bent *M'* prior to snapping into the bent *M*. For enabling the left barrel to be fired first, the trigger *A* is pushed to operate the lever *T*. The foot *t* of the lever *T* is up to the fulcrum at the end of the slot *s*; and the pressure applied to the trigger *A*, being transmitted by the pin *t'* to the lever *T*, compels the head *t'* to shove the slide *C* into its forward position. While the trigger *A* is pushed, the step *R* recedes between the walls *a* and *a'*; the step *L'*, which advances to the wall *a'*, descending into the clearance between the steps *L* and *R''*. The spring *E*

returns the trigger *A* to its original position, but with the lever *T* and the slide *C* in their altered positions. After the left barrel has been fired from the step *L'*, the right barrel can be fired from the step *R''*; the sear-tails *X'* and *x'* having been taken out of reach by the action of the left tumbler in falling. The slide *C*, if in the forward position, is shoved to its backward position by the lug *p* bearing against the lever *T*. An interval normally exists between the step *L'* and the sear-tail *X'*. This interval prevents the step *L'* arriving under the sear-tail *X'* before the spur *V* on the slide *C* is blocked by the leg *w* of the safety-bolt *W*. When the trigger *A* is pulled, the spur *V* will not clear the leg *w* unless the slide *C* is practically in one or the other of its extreme positions. In the unlikely event of the trigger being pulled with the slide *C* out of place, the spur *V* and the leg *w*, acting in conjunction to prevent the rising of the trigger, guard against the simultaneous discharge of both barrels. The prolongation *S* covers the gap due to pulling the trigger.

The catch *B'* (Fig. 11) is without steps. The base *b'* touches the trigger *A'* at *i''*. The stop *i* on the trigger *A'* acts as a step; corresponding in height with the step *R''*. The opposite stop (not included in this view) also acts as a step; corresponding in height with the step *L*. The spring *E'* is formed on the catch *B'*.

The slide *C'* is a modification of the slide *C*; being without the spur *V*. The inadvertent firing of both barrels together is guarded against by arranging that the step *L'* (Fig. 12) does not reach the sear-tail *X'* until the step *R* has cleared the sear-tail *X* (Figs. 13 and 14). With the slide *C'* in the intermediate position, though the trigger can yield to a pull, neither lock would be released.

The selective mechanism may be dispensed with; in which case only two steps at different heights (corresponding with the steps *R* and *L*) would be required. Instead of two nicks on the trigger and an arm with one point only, there may be a solitary nick on the trigger and an arm with two points.

A nose on the catch can engage with two bents on the rocker; or a nose on the rocker may engage with two bents on the catch. Instead of a catch working on the trigger-pin *a'* retaining the plunger, the right sear-tail or safety sear-tail could retain the rocker. If, when the breech is open, the thumb-lever *Y* return to its normal position, so that the safety-bolt *W* can be pressed forward both locks may, after the arm *f* has escaped from the nick *N'*, be let down together by holding back the trigger or commencing to close the gun.

It will be understood that, without departing

ing from the principle of this invention, various modifications can be effected as regards the details of the mechanism.

What I claim as my invention and desire 5 to secure by Letters Patent is:—

1. Single-trigger mechanism for double-barrel guns comprising a trigger having two walls and a nicked back, a spring-actuated rocker pivoted to the trigger-plate, an arm 10 depending from the rocker opposite the nicked back of the trigger, a catch mounted on the trigger-pin, a slide supported by two grooves in the walls of the trigger, a V-shaped spring placed between the slide and 15 the catch, a lever jointed in the trigger, the head of the lever entering a notch in the slide and the foot protruding from the trigger-walls, a bar that affords communication between the fastening lever and the spring-actuated rocker and a safety-bolt having a leg that works along the top of the trigger, 55 the fastening lever, the bar and the leg of the safety-bolt causing the parts to return to their normal positions, the trigger lifting the catch twice to free the rocker, once during the first pull and again during the involuntary pull, the movements of the trigger being controlled owing to the nicked back of the trigger bedding twice against the dependent arm on the rocker, such construction giving an extremely short release 60 65 70 after the involuntary pull, pressure at the back of the trigger serving to force the protruding foot of the selective lever against the end of the slot in the trigger-plate, thus moving the selective lever far enough to 75 change the position of the slide and reverse the order in which the barrels are fired, substantially as described.
2. Single-trigger mechanism for double-barrel guns comprising a trigger having two walls and a nicked back, a spring-actuated rocker pivoted to the trigger-plate, an arm depending from the rocker opposite the nicked back of the trigger, a plunger hinged to the rocker, the head of the plunger having two bents, a spiral spring surrounding the plunger, a catch mounted on the trigger-pin, the nose of the catch engaging in 35 the first bent of the plunger to retain the rocker in its normal position and in the second bent to retain the rocker in its intermediate position, a slide supported by two grooves in the walls of the trigger, a V-shaped spring placed between the slide and 40 45 50 the catch and adapted to hold the said slide
- in either of two positions beside answering as a trigger-spring and a catch-spring, a selective lever jointed in the trigger, the head of this lever entering a notch in the slide and its foot protruding from the trigger-walls, a bar that affords communication between the fastening lever and the spring-actuated rocker and a safety-bolt having a leg that works along the top of the trigger, 55 the fastening lever, the bar and the leg of the safety-bolt causing the parts to return to their normal positions, the trigger lifting the catch twice to free the rocker, once during the first pull and again during the involuntary pull, the movements of the trigger being controlled owing to the nicked back of the trigger bedding twice against the dependent arm on the rocker, such construction giving an extremely short release 60 65 70 after the involuntary pull, pressure at the back of the trigger serving to force the protruding foot of the selective lever against the end of the slot in the trigger-plate, thus moving the selective lever far enough to 75 change the position of the slide and reverse the order in which the barrels are fired, substantially as described.
3. Single-trigger mechanism for double-barrel guns comprising a trigger with a nicked back, a spring-actuated rocker mounted on a horizontal pivot, an arm depending from the rocker opposite the nicked back of the trigger, and a catch that retains the rocker in its normal position and subsequently in its intermediate position, the trigger lifting the catch twice to free the rocker, once during the first pull and again during the involuntary pull, the movements of the trigger being controlled owing to the nicked back of the trigger bedding twice against the dependent arm on the rocker, and means for causing the parts to return to their normal positions, substantially as described. 80 85 90 95

In testimony whereof I have signed my name to this specification in the presence of two subscribing witnesses.

JAMES W. SMALLMAN.
